INTERVAL TIMER SWITCH

Frederick Lux, Waterbury, Conn., assignor to Lux
Clock Manufacturing Company, Waterbury,
Conn., a corporation of Connecticut

Application August 28, 1934, Serial No. 741,801

18 Claims. (Cl. 200—37)

This invention relates to time-controlled apparatus, and more particularly to an interval timer adapted to operate a switch mechanism after the expiration of a predetermined period of time.

One object of this invention is to provide an electric switch mechanism which is controlled by a clock movement and has associated therewith a manually adjustable pointer for the dual purpose of closing the circuit through the switch, and winding the clock movement to cause it to operate said switch after any desired length of time.

A further object is to provide a time-controlled switch of the above nature in which the pointer is associated with means for initially locking it on the outside of the dial, making it necessary to press the pointer against the dial to close the electrical circuit before the pointer may be turned to the desired time interval setting, means being also provided whereby the pointer may be turned backwardly in case it may have been set to operate at a greater time interval than desired.

A further object is to provide an interval timer of the above nature having two independent switches which are simultaneously operated by the clock mechanism, whereby various types of electric switch connections may be accomplished.

A further object is to provide an interval timer of the above nature which will be simple in construction, inexpensive to manufacture, easy to install and manipulate, compact, ornamental in appearance, and very efficient and durable in use.

With these and other objects in view there have been illustrated on the accompanying drawings two forms in which the invention may be conveniently embodied in practice.

In the drawings:

Fig. 1 represents a perspective view of the interval timer.

Fig. 2 is an enlarged vertical sectional view through the same.

Fig. 3 is a perspective view of a portion of the dial and the pointer locking clip.

Fig. 4 is a detail perspective view of the cam member and associated locking block.

Fig. 5 is a transverse sectional view through the clock casing, showing the switch mechanism connected as a double pole switch, the view being taken along the line 5—5 of Fig. 2, looking in the direction of the arrows.

Fig. 6 is a vertical sectional view taken along

the line 6—6 of Fig. 5, and showing the switch in "closed" or operative position.

Fig. 7 is a fragmentary transverse sectional view taken along the line 7—7 of Fig. 5, showing the switch in "open" or inoperative position.

Fig. 8 is a diagrammatic view of the switch and circuit, showing the same connected as a "single pole" switch.

Fig. 9 is a diagrammatic view of the same, showing the connections for a "double single pole" switch.

Fig. 10 is a diagrammatic view of the same as it appears when connected as a "double break single pole" switch.

Fig. 11 is a fragmentary sectional view of a modified form of time switch in which the clock-work mechanism is rigidly held in the clock frame, and the pointer shaft is movable with respect to same.

Referring now to the drawings in which like reference numerals denote corresponding parts throughout the several views, the numeral 10 indicates a cup-shaped clock casing preferably made of molded insulating composition, such as "bakelite." The casing 10 has an open rear end and a closed front end 11 which constitutes the clock dial, having the usual time-indicating scale 12 marked thereupon, herein illustrated as being graduated to indicate the sixty minutes of an hour, as shown in Fig. 1.

The clock casing 10 is adapted to rest with its back upon a flat surface, such as a table top 13, and has a two-conductor "lead-in" cord 14 entering the casing 10, and a similar "lead-out" cord 15 passing out of said casing at the diametrically opposite side. The "lead-in" cord 14 is provided with a two-prong plug 16 for engagement in any convenient wall outlet 17. The "lead-out" cord 15, however, may be provided with a plug socket 15a for completing the electrical circuit through any desired power consuming device, not shown.

The mechanism of the clock includes a spring motor generally indicated by the numeral 18, and a pair of motor plates 19, 19a, held in rigid spaced relationship by pillars 20. The upper and lower portions of the motor plates are provided with aligned apertures for slidably engagement upon a pair of horizontal upper and lower posts 21 and 22. The forward ends of the posts 21 and 22 are anchored as by heading over their reduced ends 21a and 22a to a front metal plate 23 positioned within the cylindrical chamber of the casing 10, and detachably secured to

the back of the clock face 11, as by means of a pair of screws 24.

The rear ends of the posts 21 and 22 are provided with reduced threaded extremities 25 carrying nuts 26 for detachable engagement with a rear circular plate 27. The rear plate 27 is preferably made of three connected sheets of laminated "bakelite" and is adapted to fit into an annular groove 28 provided in the open rear end 10 of the casing 10.

It is to be noted from the above construction that the motor unit 18 will be slidable along the supporting posts 21 and 22, and said posts 21 and 22 with the front and rear plates 23 and 27 15 constitute a motor and switch supporting frame which may be inserted or removed as a unit from the casing whenever desired by merely removing the screws 24.

The clock motor 18 is driven by a main coil 20 spring 29 connected at its inner end to a main shaft 30. The main shaft 30 is rotatably journalled in the slidable motor plates 19 and 19a, and is provided with a reduced squared shank 31 which extends forwardly through a suitable aperture 32 25 provided in the clock face 11 and adjacent metal plate 23. A bushing 33 carrying an indicating pointer 34 is non-rotatively fitted upon the forward end of the squared shank 31.

The indicating pointer 34 is located in front of 30 the dial face 11 and is provided with a rectangular handle 35 preferably constructed of insulating material for facilitating the manipulation of said pointer and clock mechanism. The handle 35 is adapted to be held against the front surface of 35 the pointer by means of a fillister-head bushing screw 36 located in a socket 37 in said knob 35 and detachably engaging the reduced threaded end 38 of the squared shank 31.

In order to prevent the handle 35 from twisting 40 relative to the pointer 34, a pair of projecting studs 39 are made rigid to the front surface of the pointer and are adapted to fit into aligned sockets 40 provided in the adjacent surface of said handle 35.

45 To successively close the switch mechanism 41 and wind the spring 29, it will be necessary to first press the handle 35 inwardly to the dotted line position shown in Fig. 2, and then to rotate said handle in a clockwise direction until the pointer 50 reaches the desired time at which the switch 41 is to open. The power from the main spring 29 is delivered to the main shaft 30 through a friction slipping mechanism 42 in a well known manner, which construction permits the turning of 55 the indicating pointer 34 and the shaft 30 in either direction independently of the driving gear without injuring the motor unit 18.

The pointer carrying bushing 33 in its assembly upon the squared shank 31 is abutted against 60 an intermediate sleeve bushing 43 loosely surrounding said shank 31, which in turn is abutted against the adjacent face of a cam disc 44 non-rotatively mounted upon the squared shank 31. The cam 44 abuts against the shoulder formed 65 at the junction of the round main shaft 30 and the squared shank 31. This construction causes the motor unit 18 to be moved upon the supporting posts 21 and 22 whenever the pointer knob 35 is depressed.

70 In order to hold the clock movement 18 in depressed position, the cam disc 44 is provided with a radial rectangular recess 45 which is normally adapted to fit about a stop block 46 secured to the rear face of the front plate 23, as by an integral rivet 48. It will be obvious from this con-

struction that when the handle 35 is depressed, the cam 44 will be forced rearwardly with the shaft 30 to the dotted line position shown in Fig. 2. The locking recess 45 in the cam disc 44 will then clear the stop block 46, permitting the handle 35 and pointer 34 to be rotated clockwise to any desired position.

To lock the indicating pointer 34 and handle 35 in their initial or "zero" position, provision is made of a locking clip 49 located on the clock face 10 11, as best shown in Figs. 1 and 3. The clip 49 comprises an inverted U-shaped body member 50 having a pair of radial inner pointer-embracing lugs 51 and 52. The bottom legs of the locking clip 49 are provided with a pair of depending lugs 15 53 which fit into sockets 54 formed in the dial face 11, said lugs preventing the locking clip from twisting. The clip is held in position upon the dial plate 11 by a single screw 55.

The right-hand pointer engaging lug 52 is cut 20 away at its bottom edge to allow the pointer 34 to pass it when the handle 35 is depressed. The left-hand lug 51 lies in contact with the face of the dial and prevents the pointer 34 from being rotated in a counter-clockwise direction beyond 25 the zero point, and also prevents it from being rotated more than one revolution in a clockwise direction.

Switch mechanism

The switch mechanism 41, previously referred to, is adapted to be actuated by a floating depressor plate 56 of substantially thick insulating material for making and breaking the circuit through a pair of spaced "lead-in" angular connection terminal brackets 57 and 58, and a pair of "lead-out" connection terminal brackets 59 and 60 by means of a pair of movable curved spring contact strips 61 and 62 adapted to be engaged by said floating plate 56. The "lead-in" 40 terminals 57 and 58 are provided with upstanding lugs 57a and 58a having binding posts 63 and 63a screwed therein to make an electrical connection to a pair of conductors 64 and 65 of the "lead-in" cord 14, as shown in Fig. 5.

The spring contact strips 61 and 62 are provided at their fixed ends with flattened extremities 60a which are adapted to lie in flat contact with said "lead-in" terminals 57 and 58, said parts being held permanently on the inner face of the rear plate 27 by means of a pair of forwardly extending guide pins 66 having reduced rear shanks 67 provided with heads 68 seated in apertures formed within the laminated rear plate 27.

The floating depressor plate 56 is preferably provided with oppositely curved ends 69 and 69a having central recesses 70 adapted to slidably embrace the posts 21 and 22. The upper end of the floating plate 56 is provided with a pair of side apertures 71 in which the guide pins 66 are slidably fitted, and said insulating plate 56 is adapted to be normally pressed forward by means of a pair of helical compression springs 72 surrounding said pins 66. The lower end of the floating plate 56 is also urged forwardly by the free ends of the spring contact strips 61 and 62.

In order to loosely connect the floating plate 56 with the motor unit 18, provision is made of a 70 thrust block 73 preferably formed integral with the front face of said plate 56 in a central position. The block 73 is provided with a countersunk socket 74 for receiving the reduced end 75 of the main shaft 30. This construction limits 75

the forward movement of the insulating floating plate 56 which is normally held in equilibrium in the position shown in Fig. 2 under the influence of the springs 72 and resilient spring contact strips 61 and 62.

The lower extremities of each spring 61 and 62 are provided with contact buttons 76, preferably of silver, and adapted to engage with similar stationary buttons 77 positioned on the adjacent surfaces of the "lead-out" terminals 59, 60. The fixed contact buttons 77 are provided with reduced shanks 77a (see Fig. 7), secured by heads 77b within apertures formed in the laminated back plate 27.

15 The "lead-out" terminal brackets 59 and 60 are each formed with upstanding lugs 59a and 60a, mounted in which are a pair of threaded binding posts 78 and 78a for connection to a pair of conductors 79 and 80 of the "lead-out" cord 15. The "lead-in" terminal brackets 57 and 58 and the "lead-out" terminal brackets 59 and 60 are held against twisting by means of rivets 81.

While the switch 41 is illustrated in Figs. 1 to 7 as connected for a "double pole" switch, the construction of said switch is not limited to this connection, but may also be used as shown in Figs. 8, 9 and 10. In Fig. 8, by eliminating one of the switch blades 62 from the circuit, the switch may be connected as a "single pole" switch. Fig. 9 shows the switch connected as a "double single pole" switch, whereby two power consuming devices may be simultaneously operated by the same time clock. Fig. 10 shows the switch connected as a "double-break single pole" switch, in which form the arcing of the switch is materially reduced.

Operation

In operation, the timer switch will first be included in an electrical circuit, such as shown in Fig. 1, after which the indicating pointer 34 and the handle 35 will be manually depressed sufficiently to clear the lug 52 of the locking clip 49. The handle and pointer will then be rotated in a clockwise direction to the desired time interval indication, at the lapse of which the circuit is to be opened.

It is to be understood that the device may be set to operate for any interval of time from a fraction of a minute up to the maximum range of the clock mechanism.

During the operation described above, the cam disc 44 will be unlocked from the stop block 46, and the spring 29 will be wound to furnish power for driving the clock movement and returning the pointer 34 and handle 35 to their initial positions. The cam disc 44 will remain in the closed circuit position shown in Fig. 4 until the pointer has reached "zero", at which time the slot 45 on said cam disc will come into alignment with the stop block 46, and permit the switch to be restored by spring action to open circuit position.

It is to be noted at this point that the construction of the switch mechanism 41 and the controlling cam 44 is such that the space included between the contact buttons 76 and 77 in their normal separated position is somewhat less than the height of the stop-block 46. Consequently, in pushing in on the handle 35, the buttons 76 and 77 are contacted to close the circuit before the cam disc 44 has cleared the stop-block 46, and further movement inwardly of the knob 35 is necessary to unlock the cam 44 from said

block 46 so as to permit turning of the same. During this further movement inwardly, the upper end plate 56 will be tilted out of its normal vertical position, as shown in Figs. 2 and 6, to assume an inclined position as indicated by dotted lines in Fig. 6.

One advantage of the present invention is that minor variations in size of the several coating parts due to manufacture or wear will be compensated for without affecting the working qualities in any way.

Fig. 11 shows a modified form of construction wherein the motor unit 18 is held in a fixed position, and the main shaft 32 may be moved laterally independently of said unit 18. The motor unit 18 is mounted upon a tubular arbor 83 within which the main shaft 32 is slidably fitted. The motor plates 19 and 19a are supported upon posts 84 secured to the front and rear plates 23 and 27 similar to the posts 21 and 22 in the first form. The post 84, however, has a reduced section 85 upon which the motor plate 19 is held in assembled position, as by means of a pair of spacing sleeves 86.

In order to connect the stationary motor 18 with the axially movable shaft 32, said shaft 32 is provided with an intermediate projecting transverse pin 87, which is adapted to slidably engage in a pair of opposed elongated slots 88 in the tubular arbor 83. Otherwise, the construction of the modified form is identical with the first form of the invention.

While there have been disclosed in this specification two forms in which the invention may be embodied, it is to be understood that these forms are shown for the purpose of illustration only, and that the invention is not to be limited to the specific disclosures but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In an electric time-controlled switch, a frame, a floating longitudinally movable self-contained spring motor clock movement mounted in said frame, a shaft to which said clock movement is rigidly secured for axial movement therewith, but being rotatable relatively thereto, driven by said movement and projecting out of said frame, a setting handle and pointer on said shaft, an electric switch located in said frame, means connected to said shaft for closing said switch when said handle shaft and movement are axially depressed, and means to hold said shaft in depressed position and said switch closed during the operation of said clock movement.

2. In an electric time-controlled switch, a frame, a self-contained clock movement slidably and longitudinally mounted in said frame, a shaft movable longitudinally with said movement but rotatable with respect thereto and carrying a setting handle and an indicator, a switch mounted in said frame, switch closing means responsive to the manual movement of said handle and movable with said shaft, and means for holding said shaft in closed circuit position for maintaining said switch closed during the operation of said clock movement.

3. In an electric time-controlled switch, a frame, a self-contained clock movement movably mounted to slide longitudinally in said frame, a

shaft movable longitudinally with said movement but rotatable with respect thereto and carrying a setting handle, a switch mounted in said frame, switch closing means responsive to the manual movement of said handle and movable with said clock movement.

4. In an electric time switch, a base having a projecting stud, a spring metal strip having one end mounted on said stud, said strip having a movable contact on its free end, a fixed contact in alignment with said movable contact, an insulating tilting plate engaging said strip and having an aperture guided by said stud, a spring surrounding said stud and pressing against said plate whereby said plate may be tilted beyond circuit closing position.

5. In an electric time switch, a frame, a self-contained clock movement longitudinally slideable in said frame, a stationary switch contact carried by said frame, a movable contact actuated by the sliding of said clock movement, and a depressor plate spring-pressed toward said clock movement and being located between said clock movement and said movable contact for opening and closing the circuit through the switch coincident with the sliding of said clock movement.

6. In a time switch, a slideable clock movement, a stationary contact, a movable contact, and a floating plate located between said clock movement and said movable contact and actuated by the sliding of said clock movement for opening and closing said switch, spring means for pressing both ends of said plate toward said clock movement, said plate being adapted to tilt around said fixed contact as an axis after the switch has been closed to compensate for minor variations in size of the working parts.

7. In an electric time switch, a clock frame having a pair of rods extending from the front and rear thereof, a self-contained clock movement mounted to slide longitudinally upon said rods and having a main shaft provided with a handle and an indicator outside the clock dial, means initially in the path of said indicator to prevent rotation thereof until said handle and indicator are depressed, and a switch member carried by said clock movement adapted to close the circuit through a power consuming device when said handle and indicator are depressed.

8. In an electric time switch, a clock casing, a self-contained clock movement mounted to slide longitudinally in said casing and having a main shaft, a handle and indicating means on the forward end of said shaft associated with the dial of said clock, means initially in the path of said indicating means to prevent rotation thereof until said handle and indicating means are depressed, a switch, and means responsive to the sliding motion of said clock movement as a unit for closing said switch.

9. In an electric time switch, a clock frame having a dial face, a self-contained clock movement mounted for sliding movement longitudinally in said frame and having a main shaft to which said clock movement is rigidly secured for axial movement therewith, but being rotatable relatively thereto, a switch mechanism located in said frame and responsive to the sliding of said clock movement, and means for holding said clock movement in circuit closing position during the predetermined period of time for which it is set.

10. In an electric time switch, a frame having a dial face, a clock movement mounted to slide

in said frame and having a main shaft, a handle and pointer carried on the forward end of said shaft in front of said dial face, a switch mechanism adapted to be operated with the sliding of said clock movement, means for holding said clock movement in switch closing position during the predetermined period of time for which said clock movement is set, said means comprising a raised block mounted on said frame, and a cooperating cam member carried by said shaft and having a notch for engagement with said block for holding said movement in inactive position.

11. In an electric time switch, a frame, a self-contained clock movement slideable longitudinally as a unit in said frame, a stationary contact button, a spring strip fixed at one end to said frame and having a movable contact button on the free end thereof, and a floating depressor plate spring-pressed toward said clock movement and being interposed between said slideable clock movement and said spring strip for bringing said movable contact into engagement with said stationary contact when said clock movement is moved longitudinally as a unit.

12. In an electric time switch, a frame, a self-contained clock movement movable longitudinally as a unit in said frame, an electric switch comprising a pair of fixed contacts, a pair of spring strips having movable contacts and normally out of contact with said fixed contacts, and a switch closing member engageable by said clock movement for pressing said movable contacts against said fixed contacts.

13. In an electric time switch, a frame, a spring motor clock movement slidably mounted to move longitudinally in said frame, an electric switch comprising a stationary contact and a movable contact, a depressor plate spring-pressed toward said clock movement and being interposed between said clock movement and said movable contact for forcing the latter against said stationary contact when said clock movement is moved.

14. In an electric time-controlled switch, a base, a timer, means for setting said timer, a fixed contact on said base, a spring strip secured at one end to said base at a distance from said fixed contact, said spring strip having a movable contact on its free end in alignment with said fixed contact, a tiltable plate for flexing said strip to bring said movable contact into engagement with said fixed contact, and a spring engaging the base of said strip and pressing upon said tiltable plate to permit said plate to tilt beyond the circuit closing position, manually operated means to hold said tiltable plate rearwardly, and means operated by said timer to release said holding means to permit said tiltable plate to move forwardly to open circuit position.

15. In an electric time-controlled switch, a casing, a self-contained spring motor longitudinally slideable in said casing as a unit, said unit including a main shaft to which said spring motor is rigidly secured against axial movement relatively thereto but being rotatable relatively thereto, an electric switch, means operated by the sliding of said shaft axially with said motor and the turning of said shaft to close said switch, means for locking said motor in switch closing position, and means responsive to the running of said motor and operated by the rotation of said shaft for unlocking said timing circuit and open-

- ing said switch at the expiration of a predetermined time interval.
16. In an electric time-controlled switch, a casing, a spring motor longitudinally slidible in said casing as a unit, said unit including a main shaft to which said spring motor is rigidly secured against axial movement relatively thereto but being rotatable relatively thereto, an electric switch, said switch including movable and fixed contacts and spring means for pressing said movable contact toward open circuit position, means operated by the sliding of said shaft axially with said motor and the turning of said shaft to close said switch, means for locking said motor in switch closing position, and means responsive to the running of said motor and the rotation of said shaft for unlocking said motor and opening said switch at the expiration of a predetermined time interval.
17. In a timer for controlling an operable device, a casing, a clock movement longitudinally slidible in said casing as a unit, said unit including a main shaft to which said spring motor is rigidly secured against axial movement relatively thereto but being rotatable relatively thereto, spring means for resisting the sliding of said movement, means to wind said clock movement and set it for a desired time interval, means actuated by the sliding of said movement and the turning of said shaft to start the operation of said device, means to hold said movement in position to maintain said device in operation, and means responsive to the running down of said clock movement and the rotation of said shaft for releasing said movement at the expiration of the desired interval of time for permitting said spring means to return said movement to its initial position.
18. In a timer for controlling an operable device, a casing, a self-contained time-responsive unit longitudinally slidible in said casing and including a main shaft, means actuated by the sliding of said unit and the turning of said main shaft to start the operation of said device, and means responsive to the running of said time-responsive unit for stopping the operation of said device.

FREDERICK LUX.
